UNITED STATES PATENT OFFICE

BRUNO BAUER, OF VIENNA, AUSTRIA

CONCRETE-AND-IRON MULTIPLE-FLOORED BUILDING

Application filed February 9, 1931, Serial No. 514,340, and in Austria November 13, 1930.

The object of the present invention is an improvement in the construction of multiple-floored buildings, where the supporting pillars are produced of concrete-and-iron, while the horizontal girders of the skeleton consist of profile irons.

According to the invention the horizontal girders, supporting the load, are connected with the vertical longitudinal reinforcements, that is to say, they rest upon distance pieces of the longitudinal reinforcements, upon flat-, angle- or other irons welded on the same.

In the accompanying drawings, I have by way of example illustrated some forms of my invention.

Figures 1, 2 and 3 represent one of the forms,—Fig. 1, a sectional elevation,—Fig. 2, a horizontal sectional view, on the line A—B in Fig. 1,—Fig. 3, a perspective view.

Figs. 4, 5 and 6 illustrate another form, wherein Fig. 4 is a sectional elevation,—Fig. 5, a horizontal sectional view on the line C—D in Fig. 4 and Fig. 6, a perspective view.

Figs. 7, 8 and 9 embody a further form,—Fig. 7, the sectional elevation,—Fig. 8, the horizontal sectional view, on the line E—F in Fig. 7 and Fig. 9, the perspective view.

The longitudinal reinforcements 1 in the form represented by Figs. 1, 2 and 3 are round irons 1, the butts of which are joined, being welded on the outer surface of the tube-like body 3. The latter serves at the same time as a distance piece between the round iron bars. The tube-like body 3 supports the ceiling joint I-beam 7, while the secondary joist 8 is attached to the I-beam 7. The longitudinal reinforcements are encircled by wire hoopings 2. In order to maintain the continuous character of the hoopings, the same are surrounded by a kind of double spiral coupling 4. The top face of the floor is indicated by the dot and dash line 5, the bottom face by the dot and dash line 6.

The longitudinal reinforcements of the form shown in Figs. 4, 5 and 6 are represented by two U-irons 9, spaced by the flat irons 10. Upon these pieces 10, an I-beam ceiling joist 7 rests. The wire hooping 2 and the surrounding double spiral coupling 4 are formed, as shown in Figs. 1, 2 and 3.

In the form, illustrated by Figs. 7, 8 and 9, angle irons 11 are disposed as longitudinal reinforcements. Each of the U-irons 12 is screwed to two of the angles 11. The U-irons 12 represent a ceiling joist. The spirals are similar to those in the preceding forms.

In all these forms holes are formed in the stays of the ceiling joist irons, in order to receive the windings of the double spiral coupling 4. In the case, represented by Figs. 7, 8 and 9 the last mentioned spiral is tapered towards the bottom. This conical spiral forms the wire hooping of the head 65 of the column below the ceiling.

Having thus described my invention, I claim as new and desire to secure by Letters Patent—

1. In reenforced concrete construction, a vertical column comprising interconnected longitudinal reenforcing members, carrier members associated with and extending transversely to said column, said carrier members having perforations therethrough in a zone adjacent to said column, and a wire encircling said column and extending through the perforations in the carrier member.

2. In reenforced concrete construction, a vertical column comprising longitudinal reenforcing members, spacers within said column, the longitudinal members being secured to the outer surfaces of said spacers, a carrier member traversing the column and resting upon one of said spacers, said carrier member having perforations therethrough in a zone adjacent to said column and a wire encircling said column and ex-

tending through the perforations in the carrier member.

3. In reenforced concrete construction, a vertical column comprising interconnected longitudinal reenforcing members, carrier members secured to the outer sides of said column, said carrier members having perforations therethrough in a zone adjacent to said column and a wire encircling said column and extending through the perforations in the carrier members.

In testimony whereof I affix my signature.

DR. BRUNO BAUER.
